UNITED STATES PATENT OFFICE

167,415

PORTABLE ELECTRIC DRILL UNIT

Joseph A. McCabe, Chicago, Ill., assignor to Portable Electric Tools, Inc., Chicago, Ill., a corporation of Illinois

Application March 7, 1952, Serial No. 18,815

Term of patent 14 years

(Cl. D54—14)

To all whom it may concern:

Be it known that I, Joseph A. McCabe, a citizen of the United States, residing at Chicago, in the county of Cook and State of Illinois, have invented a new, original, and ornamental Design for a Portable Electric Drill Unit, of which the following is a specification, reference being made to the accompanying drawings, forming a part hereof.

In the drawings:

Fig. 1 is a top plan view of a portable electric drill unit showing my new design;

Fig. 2 is a side elevational view of the portable electric drill unit;

Fig. 3 is a rear elevational view; and
Fig. 4 is a front rear elevational view.
I claim:

The ornamental design for a portable electric drill unit, substantially as shown.

JOSEPH A. McCABE.
